UNITED STATES PATENT OFFICE.

JAMES G. SMITH, OF CLEVELAND, OHIO.

FIRE-PLACE.

SPECIFICATION forming part of Letters Patent No. 361,727, dated April 26, 1887.

Application filed December 5, 1885. Serial No. 184,840. (No model.)

To all whom it may concern:

Be it known that I, JAMES G. SMITH, a citizen of the United States, residing at Cleveland, in the county of Cuyahoga and State of Ohio, have invented certain new and useful Improvements in Fire-Places; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

15 Figure 1 of the drawings is a representation of this invention, and is a vertical section. Fig. 2 is a front view of the top portion. Fig. 3 is a back view of the front plate, and shows a corner of the back plate in position, the rest 20 of the back plate being broken away.

My invention relates to fire-place air-chambers; and it consists in the construction and novel combination of parts, as will be herein-after fully described, and particularly pointed 25 out in the claim.

Referring by letter to the accompanying drawings, A designates an air-chamber formed by a front plate, A', and a back plate, A'', joined together.

30 B is a continuous horizontal air flue formed within the air-chamber A by horizontal partitions B', which do not extend entirely across the air-chamber. This air-flue extends from the bottom of the air-chamber A to the top of the same.

35 C C, &c., are inclined air-flues passing over the top of the fire, intersecting and having communication with the horizontal continuous air-flue B.

40 D is a horizontal air-flue located at the top and in front of the top air-flues, C, intersecting and having communication with the top air-flues, C, and being provided in front with openings F for the final discharge of the heated air into the room.

45 E is a cold-air inlet located at the bottom of the air-chamber A, and having communication with the outside air and the horizontal continuous air-flue B. The office of this continuous horizontal air-flue B is to hold the air in its upward passage longer against the heated walls of the air-chamber A, that it may become more thoroughly heated by traveling a greater distance before entering the top air-flue, C.

It will be observed that the inner back wall of my "fire-place" is inclined forward from bottom to top in front of the continuous or zigzag flue B. By this construction the compartments of said flue formed by its shelving 60 are increased in size and holding capacity in regular order from the bottom upward, thereby affording constantly-increasing space for the expansion of heated air to increase the draft.

The universal objection to the air-chambers 65 now in use is, that the air rushes up the chamber so quickly that it has not time to become heated.

In the present construction the air in its upward course is made to pass four times horizontally across the back of the air-chamber A before entering the top air-flues, C, which latter flues may be increased or reduced in number, as may be desired. In some instances I use side air-chambers in connection with the 70 back air-chamber; and when this construction is used the flues B are extended and include the side air-chambers also.

G are open spaces between the top air-flues, C, for the passage of the heat and smoke into 75 the chimney or smoke-pipe above.

H is the fire-box, and I the ash-pit below. J is the heat and smoke chimney passage or flue above the top air-flues, C. Within the top horizontal air-flue, D, is located a sliding 80 damper, D', for regulating the amount of heat passing into the room and for shutting out the cold air and preventing it from entering the room, when desired.

It is obvious that the above construction is 85 applicable to open stoves as well as to fire-places, and I do so apply it in practice.

Having described this invention, what I claim, and desire to secure by Letters Patent, is—

90 The improved fire-place herein described, provided with a double back wall, the inner of which is inclined forward, the back wall being substantially vertical, as shown, the air-inlet, the continuous or zigzag horizontal flue B, the inclined flues, and horizontal top flue having discharge-openings, substantially as specified.

95 In testimony whereof I affix my signature in presence of two witnesses.

JAMES G. SMITH.
